UNITED STATES PATENT OFFICE

ALBERT LUPICA, OF NEW YORK, N. Y.

DESIGN FOR A BARBERSHOP POLE

Application filed March 15, 1933. Serial No. 47,465. Term of patent 3½ years.

To all whom it may concern:

Be it known that I, ALBERT LUPICA, a citizen of the United States, residing at New York city, in the county of New York and State of New York, have invented a new, original, and ornamental Design for a Barbershop Pole, of which the following is a specification, reference being had to the accompanying drawing, forming part thereof.

Fig. 1 is a front elevational view of a barbershop pole, showing my new design.

Fig. 2 is a side elevational view of the same.

Fig. 3 is a plan view of the same.

I claim:—

The ornamental design for a barbershop pole as shown.

In testimony whereof I have affixed my signature.

ALBERT LUPICA.
